CLAIM

The ornamental design for a beverage container, as shown and described.

DESCRIPTION

FIG. 1 is a perspective view of the beverage container; FIG. 2 is a lower perspective view of the beverage container; FIG. 3 is a front view of the beverage container; FIG. 4 is a rear view of the beverage container; FIG. 5 is a left side view of the beverage container; FIG. 6 is a right view of the beverage container; FIG. 7 is a top view of the beverage container; and, FIG. 8 is a bottom view of the beverage container. In the drawings, the evenly-spaced broken lines depict portions of the article that form no part of the claimed design; the dash-dot-dash lines represent boundaries of the claimed design and form no part thereof.

1 Claim, 7 Drawing Sheets
